HEAT TREATING CONTAINER

Angus M. Miller, Pleasant Ridge, and Harvey H. Lightle, Detroit, Mich., assignors to The Electro-Alloys Company, Elyria, Ohio, a corporation of Ohio

Application August 13, 1938, Serial No. 224,822

6 Claims. (Cl. 263—49)

This invention relates to heat treating containers such as carburizing boxes and annealing pots, more particularly to boxes of the type having walls formed of sheet or plate of heat resisting material.

In the use of carburizing boxes, metal articles to be carburized, are placed in the boxes together with any suitable carburizing agent such as bone dust. The boxes are introduced into a heat treating furnace, with suitable covers or trays, and subjected to the heat of the furnace. The heat is directed to the sides and ends of the box, to cause heating of the box, the contained articles and the carburizing agent, until the articles are heated to a desired predetermined temperature, whereupon the metal articles will absorb the carburizing agent.

The effect of the temperature which may reach from 1600° to 1800° F. is to add to the carbon contents of the surface portion of the metal articles. After the carburizing operation, the boxes are then withdrawn from the furnace and cooled and the heat absorbed by the box and the contents becomes gradually dissipated. Consequently the boxes are subjected to extreme variation in temperature and in former constructions, due to the expansion and contraction of the walls of the boxes, more particularly the side walls, these walls commonly become thermally warped, or otherwise damaged.

Also, in prior constructions there has been difficulty caused by some of the metal articles placed in a box to be carburized becoming heated to carburizing temperatures more rapidly than other articles included in the box, and also the reverse condition, when some of the articles are cooled more rapidly than other differently disposed articles, with the result that the articles are not uniformly carburized.

We have devised a carburizing box formed of cast metal and sheet or plate constructed to permit uniform distribution of heat to the interior of the box and reinforced so that a floating action of the plate forming the side walls may occur due to temperature variation without danger of permanent distortion or fracture of the walls.

It is an object of our invention therefore to provide an improved carburizing box of rugged construction whereby articles placed therein and subjected to carburizing temperatures may be more uniformly subjected to such temperatures both during the heating and cooling period.

Another object of our invention is to provide an improved carburizing box having relatively

thin walls formed of plate material of single thickness reinforced in an improved manner.

Another object of our invention is to provide an improved carburizing box having side walls formed of relatively thin plate of heat resisting material reinforced in a manner to permit of a floating action of the plate responsive to the temperature variation.

Another object of our invention is to provide an improved carburizing box which can be economically manufactured and assembled.

Other objects of our invention and the invention itself will become increasingly apparent from a consideration of the description and drawing wherein.

Fig. 1 is a plan view of a carburizing box formed in accordance with our invention;

Fig. 2 is a front elevational view of the box of Fig. 1;

Fig. 3 is a side elevational view of the box of Fig. 1;

Fig. 4 is a fragmentary sectional view taken along the line 4—4 of Fig. 1;

Fig. 5 is an enlarged fragmentary view of a corner of the box illustrated in Fig. 2 and

Figs. 6, 7 and 8 are plan, front elevational and end elevational views respectively of a portion of a reinforcing element we may employ with the box illustrated in Figs. 1, 2 and 3.

Referring now to the drawing, and particularly to Figs. 1, 2 and 3, we have shown a preferred form of our invention wherein a single plate 10 is bent into generally rectangular form and its adjacent edges welded or otherwise secured together with rounded corner portions as indicated in Fig. 1 at 11 is held in such form by corner elements generally indicated at 12. If desired the plate 10 may be formed oval or round. The corner elements 12 are alike in construction and each comprises similarly formed upper and lower members 13 confrontingly disposed and integrally secured together generally centrally of plate 10 in any suitable manner as by welding. Each of the members 13 is of arcuate form to conform to the contour of the corner portion 11 of plate 10, the upper portion of the member being formed to provide a depending inner flange 14 spaced from between to loosely receive the top and bottom portions of plate 10.

The members 13 are preferably provided with longitudinally extending slots 13a—13a permitting more efficient heating of plate 10 and decreasing the weight of the carburizing box. As best indicated in Fig. 2, the wall 15 of member 13 is extended as indicated at 17 to provide a

cooperating outer flange for the inner flange 14. Top and bottom reinforcing elements generally indicated at 18 are provided between each of the corner elements 12, and the elements 18 being 5 preferably cast metal and of U-form in cross section. The elements 18 are cut back at each end to provide a vertically extending face 19 and horizontally extending arms 20—20, the depth of the elements at the ends being increased to 10 form the arm 20. The reinforcing elements are adapted to loosely engage the top and bottom portions of plate 10 intermediate the corner elements 12 and are maintained in place by the arms 20 being hooked under the flanges 14 and 15 17 of the corner elements 12. It will be understood that in assembling the carburizing box the reinforcing elements 18 are first placed in position and that the corner elements are subsequently hooked over the corner portions of plate 20 10 to lock the reinforcing elements in assembled position by welding or otherwise securing the cooperating pair of members 13 together. The reinforcing elements 18 are not secured directly to plate 10 in any manner and the vertically extending faces 19 and arms 20 of the reinforcing elements are spaced from the flanges 14 and 17 of the corner elements 12 so that the reinforcing element 18 is permitted a limited floating action.

Thus, the side walls formed by the plate 10 may 30 expand and contract under thermal change to relatively alter the distance between corner elements 11 without interference by the reinforcing elements 18 and at the same time by providing a desired clearance between the top and bottom portion of plate 10 and the grooves 16 of the corner elements, the side walls may expand and contract in a vertical direction.

The above described construction permits a full floating action between the carburizing box side 40 walls formed by the plate 10, the corner elements 12, and the reinforcing elements 18 while at the same time the corner elements 12 and reinforcing elements 18 form a rugged cast metal frame work for reinforcing the relatively thin plate side walls. Thus, there is no danger of the plate side walls 45 being permanently warped or bent out of a plane including the reinforcing elements 18 and at the same time shocks which might be occasioned by superposing one loaded box on another are largely absorbed by the corner elements 12.

We have shown the side walls of the carburizing box as being formed of a single plate but it is understood that several plates may be used and integrally joined together so that each side wall 55 may consist of a different plate.

Although we have shown and described a preferred form of our invention, we contemplate that numerous and extensive departures may be made therefrom without departing from the spirit of our invention and the scope of the 60 appended claims.

Having thus described our invention, what we claim is:

1. A heat treating container comprising a sub-

stantially continuous one piece sheet metal wall bent to generally tubular form, vertical elements having flanged ends provided with confronting slots receiving top and bottom portions of the wall, and longitudinally slotted reinforcing elements loosely engaging top and bottom portions of the wall intermediate said vertical elements. 5

2. A carburizing box of generally rectangular form comprising sheet metal side walls, corner elements having flanged ends provided with confronting slots receiving the side walls, and reinforcing elements extending intermediate the corner elements and interlocked therewith, the reinforcing elements being slotted to receive the side walls. 10

3. A carburizing box comprising side walls formed of plate material of single thickness bent to form a generally rectangular tube, a reinforcing frame loosely supporting the side walls and permitting a floating action of the side walls 20 responsive to thermal change, said frame comprising corner elements hooked over top and bottom corner portions of the side walls, reinforcing elements telescoped over top and bottom portions of the side walls intermediate the corner elements, and means for loosely interlocking the reinforcing elements with the corner elements. 15

4. A heat treating container comprising a tubular wall structure, reinforcing elements at the upper and lower edges of said tubular wall structure and spaced from each other around the upper and lower edges and loosely engaging the wall structure, and vertically extending corner elements superposed over top and bottom corner portions of the tubular walled structure and disposed between said first named elements and interengaged therewith. 30

5. The method of forming heat treating containers which includes bending plate material to form a generally rectangular tube having arcuate 40 corner portions, telescoping grooved reinforcing elements over top and bottom portions of the tube side walls intermediate the corner portions, hooking cooperating top and bottom corner elements over the tube corner portions having portions engageable with the reinforcing elements, and integrally joining the cooperating top and bottom corner elements to provide a protective frame for the tube. 45

6. The method of forming heat treating containers which includes forming plate material into a tubular member, telescoping grooved reinforcing elements over top and bottom portions of the tube in spaced relation, hooking cooperating top and bottom reinforcing elements over the opposite edges of the tube, and between said telescoping grooved reinforcing elements and integrally joining the cooperating top and bottom elements to provide a protective frame for the tube. 55
